CLAIM

The ornamental design for an AC port transition collar as shown and described.

DESCRIPTION

FIG. 1 is a rear perspective view of an AC port transition collar showing the new design.

FIG. 2 is a top plan view of thereof.

FIG. 3 is a bottom plan view thereof.

FIG. 4 is a left elevational thereof.

FIG. 5 is a right elevational view thereof.

FIG. 6 is a front elevational view thereof; and,

FIG. 7 is a rear elevational view thereof.

The broken lines in the drawings depict portions of the AC port transition collar that form no part of the claimed design.

1 Claim, 5 Drawing Sheets
